DIRECTION FINDER LOOP

Walter Berndt, Berlin, Germany, assignor to
 Telefunken Gesellschaft für Drahtlose Tele-
 graphie m. b. H., Berlin, Germany, a corpora-
 tion of Germany

Application December 31, 1936, Serial No. 118,458
 In Germany November 9, 1935

7 Claims. (Cl. 250—33)

This invention relates to an improved direction finder loop or frame antenna for transmitting and receiving radio frequency waves.

The present invention concerns a loop or frame antenna arrangement with no, or only very small antenna effect.

As is known, the directional diagrams of frame antenna correspond to the calculated ones only if the antenna effect of frame can be success-
 10 fully eliminated. Various means are known in
 the art for accomplishing this purpose. Frame
 and input circuit may be developed symmetrical-
 ly; the frame or loop conductor may be screened
 electrically; the lead lines to the frame may be
 15 grounded over differential condensers or the an-
 tenna effect may finally be compensated by an
 auxiliary antenna. In spite of all these measures,
 the antenna effect still exists to a considerable
 extent and is always compensated by the means
 20 cited last, that is, by an auxiliary antenna. The
 antenna required must have a definite effective
 minimum height. But it is in many cases incon-
 venient to employ a large auxiliary antenna. It
 is desirable for this reason to construct frame
 25 antennas with as small as possible antenna effect.

Therefore, in accordance with the invention,
 a loop or frame is constructed in the manner
 that the leads to the frame or loop conductor
 30 ends pass through the perpendicular loop diam-
 eter to divide symmetrically the plane enclosed
 by frame. The lead line is suitably shielded
 metallically and the midpoint of the conductor
 connected with the shielding member.

An exemplified embodiment is illustrated in the
 figure. R therein is a frame or loop conductor
 35 with one coil. A pair of loop leads Z are twisted
 and connect at top points P₁ and P₂ of conductor
 R and are shielded by a metallic pipe S which
 passes through the diameter of the loop in the
 axis of rotation thereof and is connected with
 40 a mass or the earth. The midpoint of the frame
 coil or conductor R is connected with the shield-
 ing of the leads at a central point M.

A frame arrangement of this type has a very
 45 small antenna effect even when the frame is
 disposed asymmetrically to the apparatus or
 earth. Measurements with a rotatable short-
 wave receiving frame resulted for the frame mini-
 mum in a receiver input potential of 1% of maxi-
 50 mum while the usual frames showed about 10
 to 20% on the same wave range. At the same
 time, both minima of the arrangement according
 to invention are always of equal sharpness, while
 in the frames used in the prior art that sharpness
 55 is mostly different at the two sides.

A complete sharpening of the minimum may
 also be insured in the arrangement according to
 invention by means of auxiliary antenna. In
 that case, the auxiliary antenna-need is substan-
 tially smaller than in the usual frames due to
 5 the small antenna effect. Auxiliary antennas are
 usually sufficient whose limiting dimensions are
 considerably smaller than the one of the frame.

A particular advantage or object of invention
 lies in the fact that the length of the frame leads
 10 have no influence on the sharpness of the mini-
 mum.

The described principle may likewise be utilized
 for frames with several coils or conductor turns.
 The frame windings may further be electrically
 15 screened in known manner. The loop may have
 the form of a circle or a polygon; yet it may
 deviate therefrom, in particular the proportion:
 height to width. In rotatable frames it suits the
 20 purpose best to arrange the leads in axis of rota-
 tion. It is evident that all observations made
 hold true for transmitter, as well as for receiver
 frames.

In frame arrangements, in particular for very
 short waves, the connecting points of earthing
 25 and frame leads may be exchanged, in other
 words the earth line is run through the plane of
 frame in symmetric manner while the leads are
 run according to standard practice and are con-
 nected to a point of the frame located opposite
 30 the earthing point.

What is claimed is:

1. In a directional antenna system to be used
 with radio frequency wave energy having sub-
 stantially no antenna effect, a rotatable loop
 aerial comprising at least substantially one con-
 ducting turn with two open terminal ends, said
 35 loop being adapted to be energized by radiant
 wave energy and positioned with its open terminal
 ends at the highest mechanical point on said loop
 to electrically maintain a point of relatively low
 40 radio frequency potential, a connection at a cen-
 tral point on said conductor intermediate its
 terminal ends forming a point of relatively low
 potential, leads connecting said terminals to high
 45 frequency apparatus, and a metallic shield hav-
 ing its axis located in the central plane of said
 loop and extending within the confines of the
 loop aerial for enclosing and electrically shield-
 ing said leads.

2. A directional antenna comprising a rotatable
 loop having at least one conductor turn with two
 open terminal ends located at the extreme upper
 portion of said loop, a pair of leads each one of
 which is connected to one of the terminal ends

50
 55

- 5 of said rotatable loop, a metallic tube arranged to pass through the central portion of said loop and within the confines of said conductor turn, said pair of leads passing through said metallic tube to electrically divide said loop symmetrically with respect to said conductor turn to reduce the antenna effect thereon, and a conductive connection from the midpoint of said conductor turn to said metallic tube.
- 10 3. A directional antenna comprising a rotatable conductive loop having a plurality of conductor turns with two open terminal ends located at the upper portion of said loop, a pair of conductive leads arranged to pass substantially through the axis of rotation and within the confines of said conductor turns, each one of said leads connected to one of the open terminal ends of said conductor turns, and forming means for electrically subdividing said loop symmetrically with respect 15 to said conductor turns to reduce the antenna effect on said loop.
- 15 4. A directional antenna comprising a rotatable circular loop having at least one conductor turn with two open terminal ends located at the extreme upper portion of said rotatable loop, a pair of twisted conductive leads each one of which is connected to one of the terminal ends and arranged to pass through the diameter of said loop, a metallic shielding pipe disposed within the 20 diameter and axis of rotation of said loop, said conductive leads passing through said shielding pipe to electrically divide the conductor turn symmetrically to reduce the antenna effect on said loop.
- 25 5. A directional antenna comprising a rotatable loop having at least one circular conductor turn with two open terminal ends located at the extreme upper portion of said rotatable loop, a pair 30 of conductive leads each one of which is connected to one of the terminal ends of said rotatable loop, a metallic shielding pipe disposed within the diameter of said conductor turn for shielding said leads, and a midpoint conductive connection from the lower midpoint of said conductor turn and the outside of said metallic shielding pipe, said midpoint conductive connection being connected to ground.
- 35 6. A directional antenna comprising a rotatable loop having a plurality of circular conductor turns with two open terminal ends located at the extreme upper portion of said rotatable loop, a pair of conductive leads each one of which is connected to one of the terminal ends of said rotatable loop, a metallic shielding pipe located at the diameter of said conductor turns for shielding said leads, and a midpoint conductive connection from the lower midpoint of said conductor turns and the outside of said metallic 25 shielding pipe, said midpoint conductive connection being connected to ground.
7. A directive aerial comprising at least one turn of conductive material arranged substantially in a plane with the terminals of said conductive material adjacent to each other to form a substantially closed loop, means connecting a point on said conductor substantially symmetrically spaced from the terminals thereof to ground or equivalent potential, leads connected to the 30 terminals of said conductor passing across said loop substantially in said plane, a shield member enclosing said leads substantially throughout their entire length across said loop, and a connection between said shield member and said point of 35 contact or equivalent potential.

WALTER BERNDT.
